OVER FIRE AIR JET FOR STOKERS

William M. Schweickart, Bay Village, Ohio, assignor to Iron Fireman Manufacturing Company, Portland, Oreg.

Application July 31, 1944, Serial No. 547,490

1 Claim. (Cl. 110—75)

1

This invention relates generally to stokers and particularly to a means for supplying over-fire air to the combustion chamber in a furnace.

The main object of this invention is to provide a means for supplying over-fire air in order to burn as much of the coke as possible from the surface, leaving a lower temperature within the fuel bed, and thus reducing the tendency to form clinkers on the grates.

The second object is to make it possible to lower the air velocity through the tuyères, thus reducing the amount of fly ash produced.

The third object is to reduce the amount of smoke formed by forcing sufficient preheated air to impinge upon the forming coke as it emerges from the retort.

The fourth object is to provide an over-fire air jet which can be substituted for one of the regular tuyère sections and in which it is possible to use as many of the jets as desired and dispose them around the periphery of the retort to suit any specific requirement.

The fifth object is to so construct the jet that the riser portion thereof may be disposed at any desired radius from the retort center and that the horizontal connection between the tuyère section and the riser is protected by refractory material and ashes and whatever heat is transmitted thereto is absorbed by the air delivered to the jet and finally reaches the combustion.

I accomplish these and other objects in a manner set forth in the following specification as illustrated in the accompanying drawing, in which

Fig. 1 is a fragmentary plan showing a retort and a plurality of air jets in conjunction therewith.

Fig. 2 is a fragmentary section taken along the line 2-2 in Fig. 1.

Fig. 3 is a fragmentary end elevation taken along the line 3—3 in Fig. 2.

Fig. 4 is a transverse section taken along the line 4—4 in Fig. 2.

Fig. 5 is a transverse section taken along the line 5-5 in Fig. 2.

Similar numerals refer to similar parts throughout the several views.

Referring in detail to the drawing, there is shown the upper end 10 of a retort, above which is disposed a locking ring 11 for the tuyère elements 12 which are made separate for manufacturing reasons, and for expansion purposes. The tuyères 12 have the usual inturned air ports 13 which ports are downwardly inclined, and are held in position by means of the ring 11, which

engages the notch 14 formed in each element 12. Such tuyère elements are now in common use, and supply air from the plenum chamber 15 to the tuyère elements 12, from whence it escapes through the ports 13 toward the center of the fire bed.

Referring particularly to my invention, same will be seen to consist of a modified form of tuyère section 16 which differs from the elements 12 in 10 that it has an outwardly turned flange 17, from which radiates the horizontal connecting pipe 18, which extends into the flange 19 formed on the lower elbow 20 of the vertical riser 21, preferably of somewhat flattened cross section as shown in 15 Fig. 4. At the upper end of the riser 21 is formed the elbow 22, having the inturned and somewhat depressed tip 23. The tip 23 is preferably round as shown in Fig. 3, although it may assume any other desired shape. It is desirable to cover the 20 horizontal pipe 18 with a refractory material 24 to protect same. It is desirable to unite the parts 17 and 18 to clamp them in their proper relationship.

In some instances it may be found desirable
25 to draw the air supply for the riser 21 directly
from the plenum chamber or from the fan itself,
although the first described form of the device
possesses the highly desirable quality of being
insertable into any sectional tuyère and selec-
30 tively positioned about the periphery thereof, and
moreover, is easily replaced or changed should
such action be found desirable.

It can be seen from the foregoing that any coke which forms in the fuel bed is burned as completely as possible from the surface by means of the air jets 25 coming from the tips 23, thereby maintaining a lower temperature within the fuel bed and holding the ashes below the fusing point, and thereby reducing the tendency to form clinkers on the grates. It will also be seen that the presence of the over-fire jets 25 makes it possible to maintain a lower air velocity at the tuyère ports 13, thereby reducing the fly ash, which is highly desirable.

45 It will also be seen that by forcing preheated air against the forming coke column, the combustion is improved and the amount of smoke formed is greatly reduced.

In practice, it is found that the quantity of air passing from the tips 23 is normally held at approximately 40% to 50% of the total air supply. The velocity of the air leaving the tips 23 should be between 2,000 and 3,000 feet per minute.

The apparatus above illustrated and described would be the type employed in clinker type equipment.

ment, whereas when used in connection with ash removal equipment, the passageway for the over-fire air will be led upward at an angle from the top of the tuyère blocks until a diameter equal to that of the grate is reached. At that point it will pass vertically to the desired height where it is turned downward for impingement against the coke column.

I am aware that numerous attempts have been made to supply over-fire air to stokers. I therefore do not intend to cover such devices broadly but I do intend to cover all such forms and modifications thereof as fall fairly within the appended claim.

I claim:

In an underfeed stoker, the combination of a retort having means for feeding coal thereto, means defining a plenum chamber surrounding said retort, tuyère blocks disposed around said retort, having downwardly and inwardly directed air passages therethrough which passages at their outer end communicate with the plenum chamber and at their inner ends with the interior of the retort, a horizontal pipe communicating with passages in the tuyère blocks below the level at which they communicate with the interior of the retort, a refractory cover disposed over said horizontal pipe, a riser pipe communicating with said horizontal pipe having a downwardly inclined tip at its upper end, pointed toward the vertical axis of said retort and adapted

to discharge air toward a central coke column, above the top of the uppermost tuyère portion for the purpose of breaking up any coke column which may be formed therein, said riser pipe extending upwardly above the uppermost portion of the tuyère blocks.

WILLIAM M. SCHWEICKART.
